UNITED STATES PATENT OFFICE.

BENJAMIN F. FIELD, OF CHICAGO, ILLINOIS, ASSIGNOR TO THE FIELD
PATENT WATER PURIFIER COMPANY, OF SAME PLACE.

FEED-WATER PURIFIER AND SCALE-ARRESTER.

SPECIFICATION forming part of Letters Patent No. 416,032, dated November 26, 1889.

Application filed June 22, 1889. Serial No. 315,190. (No model.) Patented in England September 3, 1889, No. 13,895.

To all whom it may concern:

Be it known that I, BENJAMIN F. FIELD, of Chicago, in the county of Cook and State of Illinois, have invented certain new and useful Improvements in Feed-Water Purifiers and Scale-Arresters, (for which I have filed an application for patent in Great Britain, dated September 3, 1889, and bearing No. 13,895;) and I do hereby declare the following to be a full, clear, and exact description of the same, reference being had to the accompanying drawings, forming a part of this specification, and to the figures and letters of reference marked thereon.

15 My present invention relates to improvements in the construction of feed-water purifiers, heaters, and scale-arresters, more especially designed for use in connection with a system such as is described and claimed in my 20 prior application, Serial No. 305,123, though applicable to other systems; and it consists in certain novel features of construction, arrangement, and adaptation of parts particularly intended to adapt the apparatus for use 25 and application in connection with locomotive-boilers of the well-known forms and constructions in common use, all as hereinafter described, and pointed out in the claims.

In the accompanying drawings, illustrating the preferred form of embodiment, Figure 1 is a longitudinal vertical section through a portion of a locomotive-boiler. Fig. 2 is a longitudinal horizontal section through the boiler. Fig. 3 is a detail view illustrating the 35 supports at the front end of the boiler. Fig. 4 is a similar view showing the manner of supporting the rear end of the purifier. Fig. 5 is an enlarged transverse vertical section through the front end of the boiler, showing 40 supports and connections. Fig. 6 is a view in perspective, showing the feed-water connections. Fig. 7 is a side elevation of the front end of the boiler, showing arrangement of blow-off. Fig. 8 is a detail showing connection between rear end of heater and crown-bars. Fig. 9 is a perspective view, partly in section, of one section of the purifier. Fig. 10 is a longitudinal section, and Fig. 11 an end view, of one of the purifier-sections. 45 50 Similar letters and numerals of reference in the several figures indicate the same parts.

Particular description of the boiler proper is deemed to be unnecessary, further than to state that the one shown is typical of the general construction of locomotive-boilers in common use, A designating the shell, B the flues, C the fire-box, D the crown-bars, E the stay-rods for the flue-sheet, F the steam-dome, G the dry-pipe, and H H' the check-valves connected to the feed-water supply.

1 designates a feed-water heater and purifier, preferably constructed after the manner described in my prior application—that is to say, made in sections, each provided with internal plates or tubes, as shown in Figs. 9, 10, 15 and 11, perforated to facilitate the passage of the water and increase the area of metallic surface exposed to the action of the water, as explained in my said application. The said sections are bolted or otherwise secured together to form a sinuous conduit extending longitudinally of the boiler above the flues and partly above and partly below the normal water-line.

In order to prevent the sediment formed or deposited within the conduit 1 from being carried through into the boiler with the feed-water and to favor the separation of the heavier particles or sediment and its retention within the conduit, I form some or all of 75 the sections, as shown in Fig. 10, with the internal tubes shorter than the external tubes or conduit-section, leaving a clear space 2 at each end or at the contiguous ends of connected sections, and in the induction end of 80 each section so formed I locate an abutment 3, whose upper face is preferably tapered, as shown, in the direction in which the water is conducted when feeding. The front end or face of this abutment 3 operates to check the 85 movement of sediment along the lower portion of the conduit and to retain it at different points and beyond or between the internal plates of contiguous sections, thereby serving not only to definitely locate the 90 deposits and prevent them from being carried into the boiler, but also to aid in keeping the 95 passages between the internal tubes substantially clear of sediment. By providing the abutments with inclined surfaces the flow of 100 water in feeding is rendered more uniform and its distribution through the various pas-

sages facilitated, and at the same time but little obstruction is offered to the passage of the steam in blowing off, and the removal of the sediment by this means is rendered more 5 certain and expeditious.

While I prefer to employ the internal tubes of my prior application, as well as the abutments or retarding-plates 3, it will be obvious that either or both of these may be omitted, 10 so far as the features of inventions which are hereinafter described are concerned.

The next novel feature has relation to the arrangement of the conduit 1 within the boiler, its supports, and the connection with 15 the feed-water pipes. The conduit 1 is arranged with its induction end at the front of the boiler and extends longitudinally of the latter, substantially as in Fig. 2, where it is shown as comprising six lengths, each composed of several sections and united by suitable connections 4 at the ends of the boiler, thus forming a long conduit, through which 20 the water is conducted before being delivered within the boiler in the form of steam or 25 steam and highly-heated water.

In order to provide supports for the conduit 1 independent of the flues, and at the same time obviate the necessity for making special attachments to or otherwise interfering 30 with the integrity of the shell, I have devised the following novel mode of supporting and sustaining the conduit within the boiler and of adjusting or determining its height, so as to receive the most effective action. To 35 the front stay-rods E on each side of the dry-pipe G is attached a clamp or bracket 5—as, for example, by applying two plates 6 to the stays and clamping them securely but removably and adjustably thereto by a bolt or 40 bolts 7. To the clamp-bracket 5 is attached a vertical adjusting-rod 8, upon which is suspended a clamp 9, engaging the conduit 1. The clamp 9 may consist of a bar or plate 10, extending across the front of the boiler and 45 beneath the conduit and suspended upon the two rods 8, one on each side of the center of the plate, and adjustment may be provided for by threading the rods 8 into the clamp or brackets 5 above, and swiveling them in or 50 upon the clamps 9 or the bar 10, as shown, so that when said rods are rotated, as by application of a wrench to an angular portion 11, or by other means, the clamp 9, carrying the forward end of the conduit, will be raised 55 or lowered. The conduit may be retained securely in position upon the bar 10 by means of a superposed bar 12 and bolts 13, these elements, in conjunction with the bar 10, forming what is herein referred to as the clamps 9. 60 As it is sometimes necessary to elevate the front end of the conduit to such a degree that the inner lengths will stand with their upper surfaces somewhat above the lower face of the dry-pipe G, the upper member of 65 the clamp 9 may be formed in separate sections, as shown, to admit the dry-pipe between them. The rear end of the conduit is, in like

manner, provided with or received in an adjustable and removable clamp, represented in the drawings as comprising two members 70 16, with bolts 17, for clamping them upon the conduit. The rear clamp is also suspended upon vertically-adjustable rods 18, depending from brackets 19, secured to the hanger or yoke 20, in which the dry-pipe is 75 supported.

Provision is made for the vertical adjustment of the clamp or support for the rear end of the conduit by providing the rods 18 with swivel-connections at one end and threaded 80 connections at the other, so that as said rods are rotated the clamp, together with the purifier, will be raised or lowered, as in the case of the front clamps and opposite end of purifier. 85

As is obvious, other well-known equivalent forms of clamps for holding the conduit and adjustable connections for raising and lowering them may be substituted for those shown, the essential feature of this part of the invention residing, primarily, in the provision for suspending the feed-water conduit 1 within the boiler and above and independent of the flues, upon the stay-rods at one end and the dry-pipe support at the other, whereby these 90 parts, common to most boilers as heretofore constructed, are utilized for this purpose without involving any other or further attachments or mutilation of the boiler. 95

To assist the suspending-rods in retaining 100 the conduit in place and to prevent the twisting or bending of said rods by the longitudinal motion of the conduit, I attach to the rear end and preferably to each of the outside connections 4 a yoke or clamp 21, extending over the crown-bars D and connected thereto to prevent longitudinal motion, as by providing the rear extension of said yoke with a stud or projection 22, fitting between and engaging the opposite surfaces of contiguous crown-bars D. (See Fig. 8.) 105

As the present invention is mainly designed for application to boilers that have been in use, although equally well adapted for new boilers, special provision is made for facilitating the insertion of the feed-water heater and purifier, which operation is usually performed when the locomotive is laid up for cleaning and repair. At such times it is customary to withdraw the dry-pipe and remove 110 the flues through the opening made in the front flue-sheet by the removal of the dry-pipe. The removal of the flues is necessary in order to clean them of scale and permit the workmen to enter within the boiler for 115 the purpose of removing the crown-bars or to make repairs. 120

It is while the flues are out that I introduce, secure, and adjust the conduit 1 within the boiler, and in order to provide an exit 125 for the operator through the steam-dome, where he must enter, as well as to afford a space for him to stand while removing or repairing the crown-bars D, I make the central

portion of the rear end of the conduit 1 shorter than the flues, thereby providing an opening 25 below the rear flue-sheet and conduit, through which the workman can pass to 5 the space above the fire-box or in which he can stand while removing the crown-bars or making repairs at this end of the boiler. In order, however, that the aggregate length of the conduit shall not be materially diminished in consequence of this shortening of 10 the central section, the outer lengths are carried close to the boiler and their rear ends curved or bent on diverging lines following the enlargement of the boiler at this point, so 15 that a wider space is left between the rear ends of these outside lengths of the conduit, which is utilized by the workman in making repairs at this end of the boiler such as could not otherwise be made without removing the 20 purifier or some portion of it.

The eduction end 26 of the conduit 1, preferably formed or provided with two or more discharge pipes or openings 27, is adjustably attached to the forward stay-rod E as by an 25 adjustable hanger 28, whereby this end of the conduit can be raised or lowered relatively to the water-line or plane of the rest of the conduit, as it is of the utmost importance that the eduction or discharge end should 30 stand well above the water-line and project into the steam-space, thereby preventing the escape of the water in the boiler through the purifier when blowing out the sedimentary deposits, and also aids in effecting the 35 conversion of the water into steam before being discharged into the general circulation of the boiler. Ordinarily the feed-water appliances connected to the check-valve casings H H' on each side of the boiler deliver water through 40 openings in the shell directly into the interior of the boiler.

In applying my improved feed-water heater and purifier, I connect both check-valve casings with the induction end of the conduit 1 45 by pipes located wholly within the boiler and attached directly to the eduction-passages leading from the check-valves to the interior of the shell. One mode of accomplishing this is by providing the induction end of the 50 conduit with a pipe 31, connected by an elbow with a transverse pipe 32, which is in turn connected to the eduction pipe or orifice of check-valve H. The other check-valve H' is connected by a pipe 33 with the pipe 31, so 55 that the feed-water appliances on opposite sides of the boiler are placed in direct communication with the conduit 1 without the addition of other external fittings, and by locating the connections wholly within the 60 boiler not only can the attachment be made at comparatively slight expense, but in case any of the joints should leak no great damage or inconvenience would result therefrom.

The sediment, &c., which was deposited 65 within the conduit is removed in the usual manner by "blowing off"—that is to say, by opening an escape-pipe connected with the

induction end of the conduit, so that the steam will force its way back through the conduit.

The "blow-off" pipe is usually carried beneath the engine, the steam, water, and sediment being discharged upon the track. This is a source of some annoyance, particularly when, as is frequently the case, the blowing-off operation is performed while the engine is standing at the station, and is more particularly objectionable, or is liable to be so regarded, when, as I contemplate doing, the blow-off is more frequently used than is common, for the purpose of clearing out the purifier.

In lieu of or as additional to the usual connections provided for discharging steam beneath the engine, I connect to one of the 85 check-valve boxes, preferably the one on the right-hand side, for the convenience of the engineer, and above the valve, or between it and the boiler, a valve, preferably a globe-valve 40, controlled from the cab and governing a passage through a pipe 41, arranged to discharge the steam into the smoke-stack, whereby, after the water has been removed from the conduit, or when not present in large enough quantities to do damage, the 95 steam is allowed to escape through the conduit 1 into the smoke-stack, where it is much less objectionable than beneath the engine.

The method or mode of maintaining the supply of water in steam-boilers by delivering the feed-water in the form of steam, which is adverted to herein, is not claimed in this, but is reserved for a separate application filed September 27, 1889, Serial No. 325,238.

Having thus described my invention, what I claim as new is—

1. The combination, in a feed-water purifier such as described, of a conduit through which the water is conducted to the boiler, located within the latter and provided with 110 plates or abutments, as at 3, located at intervals in the length of the conduit and in the lower section of the opening therein, substantially as described.

2. The combination, to form a feed-water 115 heater and purifier such as described, of a conduit located within the boiler and provided with internal tubes arranged at intervals in the length of the conduit, with retarding-plates occupying the lower portion of the 120 conduit and arranged in the spaces between contiguous groups of internal tubes, substantially as described.

3. A feed-water heater and purifier such as described, consisting, essentially, of a series 125 of tubular sections united together and provided with shorter internal tubes and an inclined-face abutment 3, located in the induction end of the section, substantially as described.

4. The combination, to form a feed-water heater and purifier for application within the boiler, of a series of sections united together to form a continuous conduit, the sections

forming said conduit being provided with a series of shorter perforated tubes held separated and removed from the ends of the section to form chambers therein, with an inclined-faced plate or abutment 3, located in the induction end of the section, substantially as described.

5. In combination with a locomotive-boiler such as described, a feed-water heater and 10 purifier suspended by adjustable supports at opposite ends upon the stay-rods and dry-pipe yoke, substantially as described.

6. In combination with a locomotive-boiler, a feed-water heater and purifier suspended 15 above the flues upon adjustable and removable supports indirectly connected to the shell of the boiler above the flues, substantially as described.

7. In combination with a locomotive-boiler 20 such as described, a feed-water heater located within the boiler above the flues, clamps removably applied to the heater at or near the ends thereof, and adjustable hangers or supports interposed between the stay-rods and 25 clamp at one end and the dry-pipe yoke and clamp at the opposite end, substantially as described.

8. In a locomotive-boiler such as described, and in combination with the flue-sheet, stay 30 rods, and the dry-pipe yoke, brackets provided with adjusting-rods and connected to clamps, the latter detachably applied to the feed-water heater to support and adjust the position of the heater above the flues, substantially as described.

35 9. In combination with a locomotive-boiler such as described, a conduit extending longitudinally of the boiler above the flues and supported at each end within the boiler, and 40 an independent adjustable support for the discharge end of the conduit, substantially as described.

10. In combination with a locomotive-boiler such as described, a feed-water heater sus-

45 pended above the flues and provided with a removable clamp or clamps applied to its rear end and extending above the crown-bars, 50 said extensions being provided with a lug engaging the sides of the crown-bars to prevent longitudinal movement of the heater, substantially as described.

11. In combination with a locomotive-boiler such as described, a feed-water heater located wholly within the boiler and above the flues, 55 connections intermediate the heater and the check-valve casings on opposite sides of the boiler for placing both feed-water pipes in communication with the heater, and a pipe provided with a valve connected to one of the check-valve casings above the check-valve, 60 through which steam is discharged while blowing off to clear the heater, substantially as described.

12. In combination with the boiler, feed-water pipes, and heater, the latter located 65 within the boiler, a pipe controlled by a valve and communicating with the induction end of heater and the interior of smoke-stack, through which the escaping steam is discharged into the smoke-stack when blowing 70 off to clear the heater, substantially as described.

13. In a locomotive-boiler such as described, and in combination with the shell, the check-valve casing, and a feed-water 75 heater located within the boiler and connected with the check-valve casing through the shell, a supplemental valve mounted upon the check-valve casing and communicating therewith, and a pipe leading from said supplemental valve to the interior of the smoke-stack, substantially as and for the purpose specified.
